UNITED STATES PATENT OFFICE.

ELIHU LIPPITT, OF ZANESVILLE, OHIO.

CIRCULAR-KNITTING MACHINE.

SPECIFICATION forming part of Letters Patent No. 415,917, dated November 26, 1889.

Application filed October 6, 1888. Serial No. 287,369. (No model.)

To all whom it may concern:

Be it known that I, ELIHU LIPPITT, of Zanesville, in the county of Muskingum and State of Ohio, have invented certain Improvements in Circular-Knitting Machines, of which the following is a specification.

My invention has reference to those machines in which the widening and narrowing of the fabric for the formation of toes and other portions of stockings is automatically effected by means of supplemental rocking cams, which are acted upon and changed in position by the heels of the needles, so that they act to throw the needles into or out of action one at a time at the end of the successive courses. It has reference more especially to machines in which the rocking cams, being thrown to and fro, operate at their two ends alternately to throw the needles into or out of their operative positions, as represented, for example, in the application of Hansdoerfer and Lippitt, filed January 6, 1888, Serial No. 260,016; and the invention consists in a new and simplified mechanism for automatically controlling said cams and determining the times at which they begin and end their operations, or, in other words, for determining the commencement, duration, and ending of the narrowing and widening operations.

With the exception of the cams and my improved mechanism for controlling them, the machines may be in all respects of ordinary construction. I have therefore omitted from the drawings those customary parts which are foreign to my invention and the presence of which is unnecessary to an understanding of my devices.

The cams with which my present improvements are employed are practically identical in construction and mode of operation with the corresponding cams lettered I and L in the Lippitt and Hansdoerfer application above referred, to which reference may be had for a more detailed description thereof.

In the accompanying drawings, Figure 1 is a side elevation of the bed plate or frame, the cam-cylinder, thread-guide, and adjacent parts of an ordinary knitting-machine with my devices applied thereto. Fig. 2 is a top plan view of the same. Fig. 3 is a perspective view showing the cam-ring forming an

essential feature of the present improvements. Fig. 4 is a cross-section of the same on the line xx of Fig. 3. Fig. 5 is an outside elevation showing the lifting-cam and adjacent parts, portions being broken away. Fig. 6 is an inside face view of the cam-cylinder, lifting-cam, and adjacent parts. Fig. 7 is a vertical cross-section through the cam-cylinder on the line yy of Fig. 2, the depressing-cam being shown in its active and the lifting-cam in its inactive position. Figs. 8 and 9 are sectional elevations looking against the inner surface of the cam-cylinder, showing the depressing-cam in its different positions. Fig. 10 is an elevation of the depressing-cam and its adjuncts.

Referring to the drawings, A represents the bed-plate or base of the machine, which will have the stationary needle-cylinder mounted thereon; D, a cylinder arranged to revolve around the needle-cylinder, commonly known as the "cam-cylinder," and provided on its inner surface with the ordinary cams for raising and lowering the cylinder-needles to effect the knitting operation, and also provided with supplemental widening and narrowing cams to which my invention relates.

The foregoing parts, together with the thread-guides, the gearing for turning the cam-cylinder, and the various other necessary parts, may be constructed and adapted to operate in the ordinary manner, and may be in all respects identical with the corresponding parts in application Serial No. 260,016, above referred to.

I represents a rocking cam, commonly designated a "narrowing-cam," for automatically lifting the needles one at a time out of action, and L is a rocking cam, known as the "widening-cam," for automatically lowering the needles one at a time to their operative positions. These cams I and L correspond in form and mode of operation with the cams designated by the same letters in the Hansdoerfer and Lippitt application, and therefore require but brief explanation herein.

The narrowing-cam I is formed at its two ends with shoulders i and i' , and carried on the upper end of an arm i^2 , forming practically a part thereof and pivoted at i^3 to a vertically-movable slide i^4 , seated in a slot in

the cam-cylinder. When this slide is down, the cam is in operative position free to tip or rock from side to side, so as to throw one or the other of its ends below the path of the 5 heels of the operative needles. When the heel of an advancing needle encounters either of the shoulders, it acts to tip the cam to the opposite side. The cam acts to lift the first needle and compel it to pass upward beyond 10 an operative position; or, in other words, carries its heel above the line of the knitting-cams. At the same time the cam in assuming its new position has its end carried above the ends of the following needles, which pass 15 thereunder and operate in the same manner as if actuated by an ordinary depressing-cam. When the motion of the machine is reversed, the first needle encounters the opposite end of the cam, which is now in operative position, the effect being to lift this first needle 20 out of action and tip the cam to its original position, so that the remaining needles pass thereunder in precisely the same manner as in the Lippitt and Hansdoerfer machine. A 25 spring i^5 , secured to the cam-cylinder, rides on the upper end of the cam-supporting arm i^2 , as shown in Fig. 5, to hold the cam in its two operative positions alternately. When the narrowing operation is completed, so that it is 30 no longer required to diminish the number of operative needles, the cam I is rendered inoperative by lifting it bodily so that both ends stand above the path of the needle-heels. For this purpose I employ an external cam-ring K, 35 (shown detached in Fig. 3,) forming the essential feature of the present invention. This ring is arranged to revolve loosely in suitable supports around the outside of the cam-cylinder, and is formed on its top with annular 40 cam-surfaces, as shown in Figs. 5 and 7, one of which rides beneath and against the cam-supporting arm i^2 . This cam-surface consists of an elevated portion k and a depressed portion k' , each extending about half-way around 45 the ring. The cam-ring is caused by means hereinafter described, or other equivalent means, to revolve slowly around the cam-cylinder. During one-half of its revolution, while the depressed portion k' bears beneath 50 the arm i^2 , the cam I is permitted to remain down in its operative position, as in Figs. 5 and 6; but during the remainder of the revolution of the ring, while its surface k bears beneath the arm, the cam is held up in the 55 position indicated by dotted lines in Fig. 6 and full lines in Fig. 7, so that it is inoperative. The cam-cylinder and the base portion of the usual thread-guide screwed to its outside are provided immediately over the arm 60 i^2 with converging surfaces i^8 , which act as the arm is lifted to bring it to an intermediate or vertical position, so that the cam I will assume the position shown in dotted lines in Fig. 6, with its two ends on a level. The 65 essence of the invention in this connection consists in the cam-ring arranged to raise and lower the narrowing-cam I, and it is manifest

that to this end the ring may bear either directly against the arm i^2 or against its supporting-slide i^4 , or be arranged in any similar 70 manner, provided it acts to raise and lower the cam I.

The widening-cam L, by which the needles are brought successively into the field of operation, is carried, as shown in Figs. 7, 8, 9, 75 and 10, on the lower end of a vibratile arm l , pivoted at l' to the cam-cylinder or other suitable support. The cam is formed at its two ends with shoulders l^2 and l^3 to override the heels of the needles. When the cam is in 80 operative position, one end stands at a higher level than the other in such position that as the needles advance the foremost needle will underride the raised end, and, acting against the shoulder, will have the effect of 85 tipping the cam to the opposite side, the first needle being depressed by and passing under the cam, while those which follow after override the cam and remain out of action. The cam being moved by the needle, which is thus 90 brought into action, has its opposite end raised in position to depress the foremost needle at the opposite end of the series when the motion of the machine is reversed, the action in this regard being the same as in the Lippitt and 95 Hansdoerfer machine. This cam has no vertical motion, but is rendered active and inactive by means of two vertically-movable wing cams or switches M and M', located on opposite sides of the cams, which serve to direct the heels of the operative needles below or above the operative end of the cam L, as occasion may require. The wing-cams are pivoted at their inner ends, as shown at l^0 , 100 Figs. 8 and 9. When their outer ends are 105 depressed, they underride the heels of all the needles, so that all the needles continue their course upward over the widening-cam, unaffected thereby. When both the wing-cams are elevated, they override the heels of the 110 needles, bringing them down within reach of the operative end of the cam L, which in the manner already described acts upon the first needle only to effect its depression to an operative position. The action of these parts 115 is essentially the same as in the original machine; but in place of the original devices for throwing the cams into action I attach to the outer ends of their respective pivots or journals arms l^4 and l^5 , Fig. 1, which ride 120 upon an annular cam-surface l^6 l^7 , formed upon the ring K. Springs l^8 act to depress these arms and to hold the cams when free in their upper positions. (Shown in Fig. 9.) The cam-surface has its portion l^6 of higher 125 level than the remaining portion l^7 . When the portion l^6 is passing beneath the arms, the cams M M' are permitted to remain in their elevated position; but when the portion l^6 underrides the arms they are lifted thereby 130 and the cams M M' held down so that the needles will pass thereover. In this way the action of the widening-cam on the needles is automatically determined.

Manifestly the form of the arms l^4 l^5 or the equivalent connections between the ring-cam and the switch-cams may be modified in form and arrangement within the range of mechanical skill, the only requirement in this regard being that the ring-cam shall serve to raise and lower the switch-cams upward and downward at the proper times.

From the foregoing description it will be understood that the single ring-cam K serves to control both the widening and narrowing cams. Its cam-surfaces are so arranged in relation to each other and to the parts upon which they act that the widening and the narrowing cams are thrown into action alternately, the narrowing-cam carrying the needles successively out of operation and the widening-cam thereafter returning the same needles one at a time into action.

The ring-cam K may be turned by hand or by any appropriate mechanism; but I recommend the simple arrangement represented in the drawings, in which it will be perceived that the ring is provided with a series of ratchet-teeth k^6 , which are engaged by a retaining-pawl k^7 and by an actuating-pawl k^8 , carried by an arm k , pivoted at k^{18} to an ear k^{19} , fixed to the cam-cylinder. As the cam-cylinder revolves the arm k^9 is carried against and past a stationary dog or trip k^{10} . In passing this trip the arm is turned on its pivot in the direction indicated by the arrow in Fig. 2, and its pawl k^8 caused to give a slight movement to the ring-cam K. A spring k^{11} , connecting the pawl k^8 with its carrying-arm, serves to return the arm to its normal position after it has passed the trip. The trip k^{10} is mounted on the longitudinally-adjustable support k^{12} , slotted and confined by screws k^{20} to a rigid support k^{13} . By adjusting the support k^{12} endwise the trip may be caused to project a greater or less distance into the path of the arm k^9 , so as to give the latter a greater or less movement upon its pivot, and thus impart a greater or less movement to the ring-cam K. In this way the machine may be adjusted to continue the widening and narrowing operations for a longer or shorter period—that is to say, through a greater or less number of courses—as occasion may require. The trip k^{10} is commonly pivoted as shown, and held in its normal position against a stop-pin k^{14} by a spring k^{15} . This arrangement is adopted to prevent breakage of the parts as the cam-cylinder is turned to and fro or revolved in a backward direction, the yielding of the trip permitting the arm k^9 to pass backward without meeting resistance.

The arm which carries the widening-cam L enters a notch in the upper edge of a horizontal slide n' , carrying two cams N and N', in the same manner as in the original machine, and for the purposes therein described. These features have no relation to the present invention.

In order that any required number of cylinder-needles may be lifted at one operation

out of action or returned by a single operation to the knitting position the present machine is provided, like the original, with the needle-depressing cam or finger H and with the lifting cam or finger G mounted on the inside of the cam-cylinder, respectively above and below the ordinary path of the needles.

The depressing-cam H has its journal h^3 extended through the cam-cylinder, as shown in dotted lines in Fig. 2, and provided on the outside with an operating arm or handle h . A spring h' , secured to the outside of this handle, bears a pin h^4 , passing through the same to bear in or against the outside surface of the cylinder, whereby the arm may be locked in different positions to hold the cam up or down, as occasion may require.

The lifting-cam G has its journal g^{20} extended in like manner and provided with a corresponding arm g^{21} , having an outside spring g^{22} , carrying a pin to bear in or against the outside of the cylinder. It also has a similar locking device. This avoids the necessity of using the springs of the Hansdoerfer and Lippitt machine to hold the cams G and H in their normal position.

To prevent the elevated needles from tipping outward before the cam H acts upon their heels, I hinge to the top of the cam-cylinder, as in the original machine, a plate g^6 to support the needles on the outside immediately above the cam H, and I hinge this plate so that it may be swung outward when the needle-cylinder is to be lifted from the machine. In place of the original device for locking this plate in position, I now provide it with a pivoted horizontally-movable arm g^3 , which may be turned outward, as in Figs. 1 and 2, to bear on the rigid ear or plate rising from and forming practically a part of the cylinder. When turned to the position indicated by dotted lines in Fig. 2, it releases the plate g^6 , so that it may be turned upward, as in Fig. 7. The thread-guide z is also hinged to turn backward out of the way when the needle-cylinder is to be removed.

Having thus described my invention, what I claim is—

1. In a knitting-machine, and in combination with the usual cam-cylinder, the narrowing-cam I, adapted, as described, to be rocked to and fro by the needles, its vertically-movable support i^4 , and the revolvable ring K, provided with cam-surfaces, whereby the raising and lowering of the narrowing-cam is effected.

2. In combination with the cylinder having the converging surfaces i^8 , the vertically-movable slide i^1 , the cam with its supporting-arm i^2 , pivoted to the slide, and the ring K, provided with cam-surfaces to raise and lower said arm, whereby the cam is automatically lifted out of action and held in an intermediate position during the required periods.

3. In a knitting-machine, the usual cam-cylinder, the widening-cam L, adapted, as described, to be rocked to and fro by the needle-heels, in combination with the wing cams

or switches M M', their controlling arms and springs, and the ring-cam to adjust said switches mounted on and revolvable around the cam-cylinder.

5 4. In combination with the cam-cylinder and the toothed cam-adjusting ring K thereon, the lever and pawl to turn the ring, the trip, and means, substantially as shown, for adjusting said trip endwise, whereby the pawl

10 may be given more or less throw at will.

5. In combination with the cam-cylinder and the automatic narrowing-cam movable vertically therein, the automatic widening-cam, the movable wing-cams at its sides, the

ring K, revolvable with and around the cylinder and provided with cam-surfaces shouldered, as described and shown, to cause the operation of the widening and narrowing cams alternately, and connecting devices, substantially as shown, between the ring and the cams. 15 20

In testimony whereof I hereunto set my hand, this 21st day of June, 1888, in the presence of two attesting witnesses.

ELIHU LIPPITT.
